UNITED STATES PATENT OFFICE.

ALBERT E. WILLIAMS, OF JERSEY CITY, NEW JERSEY, ASSIGNOR TO ELECTRIC LIQUID OPERATOR COMPANY, OF JERSEY CITY, NEW JERSEY, A CORPORATION OF NEW JERSEY.

CIRCUIT-CLOSER.

1,194,324.

Specification of Letters Patent.

Patented Aug. 8, 1916.

Application filed August 19, 1914. Serial No. 257,453.

To all whom it may concern:

Be it known that I, ALBERT E. WILLIAMS, a citizen of the United States, residing in Jersey City, Hudson county, and State of New Jersey, have invented certain new and useful Improvements in Circuit-Closers, of which the following is a specification.

The object of my invention is to provide an electrical device which is positive in its action, whereby a prescribed water level may be maintained within a tank or other receptacle, and in case such water level falls below a prescribed point, an alarm or other electrical device will be operated either to attract the attention of the proper party in charge of the tank, or an electrical pump or other mechanism released to re-fill the tank to its proper level.

The invention consists in inclosing two electrodes of conical shape, one within the other within a chamber or compartment, each of said electrodes being composed of a metal of high conductivity, means for electrically connecting said electrodes with a source of electricity, means for adjusting one electrode with relation to the other, and in means for connecting the device to a tank or other receptacle for containing a liquid.

The invention also includes the forming of the electrodes of conical shape, the perforation of the same to allow of an uninterrupted flow of the liquid between them, and in other special features of construction and arrangement of parts hereinafter described and claimed specifically.

In the accompanying drawings, Figure 1, is a sectional elevation of my new device showing it connected to a water tank which is partially broken away, an electrical circuit, motor, pump and other devices being shown diagrammatically; Fig. 2, is a cross section on plane of line 2—2, Fig. 1.

It is to be understood that I do not limit myself to the identical form and structure of device herein shown, as many mechanical expedients may be resorted to without departing from the spirit and intent of my invention.

In the drawings A, represents a portion of a tank or other receptacle for containing a liquid, to which my signaling device B, may be attached.

The device B, consists of a cylindrical or other shaped casing b, of non-conducting material, provided with the upper and lower

flanged plates b', b'', forming a compartment b'', inclosing the electrodes E, E'.

To the upper flanged plate b', is adjustably connected the inverted cone-shaped electrode E, composed of metal of high conductivity. To the lower flanged plate b'', (but insulated therefrom as at b'') is permanently connected a second electrode E', of conical shape also formed of metal of high conductivity.

Both of the electrodes E, E', as shown in the accompanying drawings have the perforations e, e', the purpose of which will be more fully explained.

The electrode E, is made adjustable with relation to the electrode E', by means of the adjustable threaded rod r, connected to the cross bar e', on the upper end of the electrode E, and the adjusting nuts r', r''.

The electrode E', is permanently held in the lower or bottom flanged plate b'', but insulated therefrom by insulation b''. This electrode is conical-shaped, and at its lower extremity is formed with an opening p, into which a pipe p', enters and connects the device to the tank A, thus permitting of the liquid or other fluid to enter the compartment b''. This pipe p', is also insulated from the tank A, at p''.

Both electrodes E, E', are preferably though not necessarily perforated as at e, e', for the purpose of permitting of a free and unobstructed circulation of the water or other liquid between them, thus insuring an electrical circuit which may be regulated as to density by adjusting the electrode E.

The upper electrode is adjustable so that the gap between the same and the lower electrode can be increased or decreased to meet the various density of the liquids or waters that contain various quantities of saline matter which increases the amperes or current flowing across the gap and overcomes the different resistance by the surface saturation of the electrodes. The formula of passing electricity through pure water requires 1800 volts to force one ampere through one cubic inch of water per square inch of electrodes, therefore the gap between the electrodes regulates the water level so desired by the current flow of electricity to its general use.

For the purpose of more clearly illustrating the practical adaptation of my invention to an automatic means for re-filling

the tank when the water falls below the water line W—W, I have shown diagrammatically in the drawings, a solenoid L, interposed in the electric circuit w, w'.

- 5 Upon the tank being filled with water to the proper level W—W, and the water in the compartment b³, having attained the same level, the electric circuit between the electrodes E, E', is closed and through the magnetic influence of the solenoid L, the pivoted arm l, is attracted to the solenoid, away from the contact point t, thereby breaking the electrical circuit with the motor M, which in turn is connected to a pump P, or any other 15 mechanical expedient for supplying water, causing the pump P, to stop supplying water through the pipe P' to the tank A. Thus the parts will remain in this position until the water in the tank A and in the compartment b³, again falls below the water level 20 W—W, in which case the circuit between the electrodes E, E', is again broken, the pivoted arm l, released from the solenoid L, closing the circuit between the motor M, 25 starting the pump P, thereby re-filling the tank A, until it again is filled to the proper water level, when the above operation is repeated.

The adjustment of the electrode E, by 30 means of the adjusting rod r and nuts r', r'', with relation to the electrode E', is an important feature of my invention, as it permits of regulating the current between the electrodes with relation to the potential, so 35 that almost any desired degree of electrical current may be obtained.

The conical shape of the electrodes is another important feature in that I am enabled to make an electrode of large surface 40 of conductivity.

I have herein described my device in connection with maintaining a water level, but it is obvious that other liquids or fluids may

be used with like result and it is to be understood that I do not limit its use to 45 water.

What I claim as my invention and desire to secure by Letters Patent is,

1. In a device of the character designated, in combination with a tank or receptacle 50 for containing a liquid, a casing connected with said tank inclosing two electrodes of conical shape, means for maintaining an electric circuit between said electrodes, for the purpose described. 55

2. In a device of the character designated, in combination with a tank or receptacle for containing a liquid, a casing connected with said tank and inclosing two electrodes of conical shape, means for adjusting one 60 electrode with relation to the other, means for maintaining an electric circuit between said electrodes for the purpose described.

3. In a device of the character designated, in combination with a tank or other receptacle for containing a liquid, a casing connected with said tank inclosing two electrodes of conical shape, each of said electrodes being perforated for the purpose described, means for maintaining an electric 70 circuit between said electrodes.

4. In a device of the character designated, in combination with a tank or other receptacle for containing a liquid, a casing connected with said tank inclosing two electrodes of conical shape, means for adjusting one electrode with relation to the other, each of said electrodes being perforated for the purpose described, means for maintaining an electric circuit between said electrodes, for the purpose described. 75

ALBERT E. WILLIAMS.
